DESIGN FOR AN AIRPLANE

Raymond D. MacCart, Warminster, Pa., assignor
to Brewster Aeronautical Corporation, Johns-
ville, Pa.

Application October 23, 1942, Serial No. 108,601

Term of patent 14 years

To all whom it may concern:

Be it known that I, Raymond D. MacCart, a citizen of the United States, residing at Warminster, in the county of Bucks and State of Pennsylvania, have invented a new, original, and ornamental Design for an Airplane, of which the following is a specification, reference being had to the accompanying drawings, forming part thereof.

Fig. 1 is a top perspective of an airplane embodying my new design;

Fig. 2 is a top plan view of the airplane of Fig. 1;

Fig. 3 is a front elevational view; and
Fig. 4 is a side elevational view thereof.

The characteristic features of the present design reside in the portions shown in full lines in the drawings.

I claim:

The ornamental design for an airplane, as shown and described.

RAYMOND D. MACCART.
